(57) **CLAIM**

The ornamental design for a slider knob, as shown and described.

DESCRIPTION

FIG. 1 is a perspective view of the front, top and right side of a slider knob showing my new design;

FIG. 2 is an enlarged view of the design taken at line 2-2 in FIG. 1; and,

FIG. 3 is an enlarged, top plan view of FIG. 2.

The dash-dash broken lines shown in FIG. 1 are included for the purpose of illustrating the environment of the slider knob and features of the slider knob that are not claimed. The features shown in dash-dash broken lines form no part of the claimed design.

The dash-dot broken lines in FIGS. 2 and 3 show the extent of the sections 2-2 from FIG. 1.
